(Cl. D54—5)

FIG. 1

FIG. 2

FIG. 3

FIG. 4

FIG. 5

FIG. 6

FIG. 1 is a plan view showing the tread of a horseshoe embodying my new design, the nail receiving apertures of the horseshoe being shown in broken lines;

FIG. 2 is a front elevational view thereof;

FIG. 3 is a side elevational view thereof;

FIG. 4 is a side elevational view, partly broken away, taken generally along line 4—4 of FIG. 1;

FIG. 5 is a plan view showing the tread of another embodiment of a horseshoe according to my new design with its nail receiving apertures shown in broken lines; and

FIG. 6 is a side elevational view, partly broken away, taken generally along line 6—6 of FIG. 5.

The dominant features of my design reside in the portions shown in full lines.

I claim:

The ornamental design for a horseshoe, as shown and described.
